Primary Examiner — Jennifer L. Watkins*(74) Attorney, Agent, or Firm* — Lowenstein Sandler LLP(57) **CLAIM**

The ornamental design of a arch support with sleeve, as shown and described.

DESCRIPTION

FIG. 1 is a bottom perspective view of an arch support with sleeve, in accordance with an embodiment of the claimed design;

FIG. 2 is a top perspective view thereof;

FIG. 3 is a bottom plan view thereof;

FIG. 4 is a top plan view thereof;

FIG. 5 is a side view thereof;

FIG. 6 is an opposing side view of FIG. 5;

FIG. 7 is a front elevation view thereof;

FIG. 8 is a rear elevation view thereof;

FIG. 9 is a bottom perspective view of the arch support with sleeve worn on a foot, the foot shown in broken lines and forming no part of the claimed design; and,

FIG. 10 is a side perspective view of the arch support with sleeve worn on a foot, the foot shown in broken lines and forming no part of the claimed design.

The portions of the arch support with sleeve shown in broken lines form no part of the claimed design.
